(57) CLAIM

The ornamental design for a wrist watch, substantially as shown and described.

DESCRIPTION

FIG. 1 shows a perspective view of the wrist watch;

FIG. 2 shows a perspective from the rear side of the case of the wrist watch;

FIG. 3 shows a front view of the wrist watch;

FIG. 4 shows a left side view of the wrist watch;

FIG. 5 shows a rear view of the wrist watch;

FIG. 6 shows a right side of the wrist watch;

FIG. 7 shows a top view of the wrist watch from VII of FIG. 3; and,

FIG. 8 shows a bottom view of the wrist watch from VIII of FIG. 5.

The broken lines showing a portion of a watch strap are for illustrative purposes only and do not form part of the claimed design.
